FUEL APPARATUS

Application filed August 18, 1923. Serial No. 658,134.

The present invention relates to apparatus or devices for supplying fuel of more or less fluidal or pulverized character to a place of combustion.

5 Among the objects of the invention are to provide a device of the character disclosed for grinding or pulverizing fuel to a given fineness, preferably pneumo-mechanically; to provide for controlling or regulating the degree of fineness or separation of 10 the pulverized fuel as desired or as proper combustion may require; to provide for controlling or regulating the rate of the grinding or pulverizing the fuel in accordance 15 with the demand made upon the device or apparatus and the character of fuel to be supplied to the combustion device; to provide for regulating admission of a supporter of combustion, such as air, to the separated 20 fuel; to provide for maintaining the desired or given grade of separation or fineness with varying quantities and with varying qualities of fuel handled by the apparatus; to provide, specifically, the combination of a 25 grinder, means for regulating the amount of fuel supplied to the grinder, a separator for effecting the separation of the ground or pulverized fuel of given or desired fineness, and a feeding means, the latter having 30 means to produce an air current through the grinder and the separator for pneumatically effecting the separation, and the separators having means for regulating the rate of 35 flow of the air and also regulatable means for admitting additional air into the separator in quantities depending upon the proportion of air and fuel required for efficient combustion; and to provide for such other and further objects, advantages and capabilities as may later appear and are inherently possessed by the invention.

In the drawings, illustrating, by way of example, a preferred form of device or apparatus for carrying out the invention, Fig. 45 1 is a front view, partly in broken section, of an apparatus constructed in accordance with the invention; Fig. 2 is a top plan view of the same; Fig. 3 is a side view of the same; Fig. 4 is a side view opposite 50 from that shown in Fig. 3, of the same;

Fig. 5 is a vertical sectional view through the apparatus; and Fig. 6 is a vertical sectional view taken at right angles to the sectional view of Fig. 5.

Referring more particularly to the drawings, wherein the invention is illustrated by a preferred embodiment, the apparatus is shown as supported upon a base 1 and consisting generally of a grinder 2, a separator 3 and a feeder 4.

The grinder or grinding unit 2 comprises a casing 5, preferably of sheet metal and secured, as by riveting, to side walls 6 and 7 of the grinding device. The separator is located above and secured to the top of the 65 grinder and comprises a main body portion 8 forming an expanding chamber and provided at its upper end with a discharge or outlet conduit 9 leading to an intake opening 10 of the feeding means, the 70 latter having a casing 11 vertically supported upon the base 1 by means of brackets or feet 12, the grinder being also supported upon the base by means of similar brackets 75 or feet 13.

The grinder and the feeder form parts of a single unitary device and are located in alignment with each other so that both will receive a common or single shaft 14 for operating both parts. The shaft is suitably 80 supported in bearings 15 and 16, as clearly shown in Fig. 5 of the drawing; and may be driven by any suitable means from any power source. Within the grinder casing 5 and fixed to the shaft is a grinding wheel 17 comprising a plurality of grinding bars or hammers 18 suitably connected to the portion 17 whereby the rotation of the grinding element will affect the bars 18 so that they 85 will act centrifugally against a series of bed-bars 19 for the purpose of grinding or pulverizing the material or fuel fed into the casing of the grinder, as the shaft and the grinding wheel rotate. The grinding bars 90 19 are arranged in spaced relation and about the periphery of the grinding wheel, a suitable entry 20 being provided in a portion of the series of bars whereby the fuel to be 95 ground may enter into the space between 100

the grinding wheel and the grinding bars 19.

The fuel to be ground is supplied in any suitable manner to a hopper 21 secured to or forming a part of a side of the apparatus as clearly shown in Figs. 2, 4 and 6 of the drawings. At the lower end of the hopper is provided a discharge opening in which is located a rotating member 22 having a plurality of radial blades fastened to a shaft 23 extending outwardly through the casing and provided at its upper end with a driven pulley 24 by which it may be rotated by any suitable means such as a power belt. The member 22 constitutes a valve of the paddle wheel gate type, and is located in the discharge opening of the hopper and operated at a predetermined or given speed to feed the fuel, to be ground, at a given rate into the grinding device.

The material when being ground is projected radially outwardly through the spaces between the bars 19 and upwardly into the expansion chamber 8 as indicated by the arrows in Figs. 5 and 6 of the drawings. For the purpose of aiding in separating the proper size of ground fuel to be eventually fed to the furnace, an air blast is made use of which will act to carry the 20 properly pulverized particles along with the air current and permit the coarser particles to fall back into the grinding device. Within the expansion chamber is provided an inclined wall 25 directed downwardly toward the inlet end portion of the grinding device to return, by gravity, the larger particles so that they will be again ground in the grinding unit. The blast of air, above mentioned, is permitted to enter through 30 openings 26 and 27 formed in the side walls 6 and 7 of the grinding device, each one of these openings being provided with slideable shutters 28 and 29 supported in guide tracks 30 and 31 suitably secured to the side walls 6 and 7 as clearly shown in Figs. 1, 3, 4 and 5 of the drawings. These shutters may be manually adjusted to vary the inlet openings between the inner edges thereof for the purpose of regulating the amount of air that 50 will be drawn into the grinding unit. The air is drawn therein by the rotation of the grinding wheel 17 and caused to move radially between the hammers 18, by centrifugal action and through the spaces between the bars 19 and into the expansion chamber 8. This action is also aided by the suction produced by the feeding device 4 described more in detail later.

If it be desired to admit an additional 60 amount of air, for the purpose of giving a correct mixture of air and fuel for proper combustion, the upper end of the mixing chamber is provided with an air inlet port 32 the effective opening of which may be 65 regulated by a butterfly valve 33 suitably

pivoted upon a shaft 34 mounted transversely in the opening 32, as clearly shown in Figs. 3 and 5 of the drawings. Opposite the opening 32 is a discharge opening 35 connected with the passage 39, the latter 70 preferably tapering downwardly and discharging into a central opening 10 of the feeding device 4.

The feeding device comprises a rotary wheel 37 having radially extending vanes 38 which operate, when rotated, to produce a suction through the passage 9 and hence in the expansion chamber 8, this suction aiding the inflow of air through the grinding device and the bars 19 and drawing the separated particles of the fuel into the blower 4. The rotating of the wheels 37, aside from creating a suction, also produces a discharge current, by a centrifugal action, into the casing 39 of the feeding device 4 80 and then through a discharge passage 40 leading to the interior of the furnace where the fuel is to undergo combustion. See Figs. 2 and 4 of the drawings.

In operation, the fuel, which is preferably crushed and dried, and which may be of any kind of fuel, such as coal, peat, or other grindable fuel, is fed or supplied to the hopper 21. The gate 22 is then rotated at a given or predetermined speed depending upon the demand made by the furnace so as to feed and measure out, at a definite rate, the fuel from the hopper into throat 20 of the grinding device. This fuel is then moved into the spaces between the hammers 18 and acted upon by centrifugal action of the grinding wheel to force the material to the periphery thereof and the inner side of the bars 9 where the hammers, owing to centrifugal action, grind the material between the edges of the bars 19 and the ends of the hammers 18. At the same time a blast of air is created by the movement of the grinding wheel as well as by reason of the suction produced by the blower wheel 37 110 and the ground fuel is forced upwardly through the spaces between the bars 19 into the expansion chamber 8. It will be noted that the expansion chamber is of sufficient capacity to permit the air draft to separate from the fuel thrown into it, the finer particles which may be carried away with the air, in suspension, and the heavier particles will have a chance to fall and return into the grinding machine to be again pulverized together with the fuel being fed by the valve 22 into the grinding unit.

The separated particles of fuel together with the air, then pass through the discharge conduit 9 and into the central portion of the blower 4. The rotation of the wheel 37 acts, by centrifugal action, to cause the material to be forced through the discharge passage 40 and fed into the furnace. During the passage of the material from the 125

expansion chamber into the conduit 9 the valve 22 may be so regulated as to admit additional air so that the proportion of air to fuel will be the proper amount for correct combustion in the fire chamber of the furnace.

It will be apparent from the above description and the illustration upon the drawings that the grinder wheel and the blower wheel are both secured to a common shaft and operated as a single unit. It will also be apparent that the blower and the grinder are separated and connected to the expanding chamber and the conduit 9 instead of having the blower acting within the chamber of the grinder. The advantage of this is that the separation of the finer particles is made far more efficient than when the two are acting in the same chamber and where larger particles would necessarily be drawn into the blower, which would be a disadvantage when it is desired to obtain a fuel of given fineness.

While I have herein described and shown upon the drawings a preferred embodiment of the invention, it is to be understood that the invention is not limited to the grinding of fuel but is applicable to the grinding or pulverizing and the separation of any other kind of material, nor to the particular arrangement of parts, details and constructions shown and described, but that other constructions, details and arrangements of parts may be comprehended by the invention without departing from the spirit thereof.

Having now described my invention, I claim:

1. A fuel apparatus comprising a rotatable shaft, a pulverizer and a blower mounted on said shaft, a hopper in communication with said pulverizer, means in said hopper for positively and regulatably feeding material into said pulverizer, an expansion chamber, a perforated surface against which the material is ground and through which the fine particles are carried into said expansion chamber, means for regulating a flow of air through said pulverizer into said expansion chamber, a duct connecting said expansion chamber to said blower, and regulatable means for admitting air directly into said chamber for varying the volume of the mixture and the proportions of pulverized material and air.

2. In a fuel apparatus a pulverizer, an expansion chamber connected to said pulverizer and adapted to cause the coarser particles to settle out of the air stream, regulatable means for admitting air into said expansion chamber through said pulverizer, means for conducting a mixture of pulverized material and air from said chamber to a place of combustion, and regulatable means for admitting air directly into the

expansion chamber for regulating the separation of coarse and fine particles in said chamber.

3. In a fuel apparatus, a pulverizer, an expansion chamber located above said pulverizer, said pulverizer having an aperture for the admission of air, a blower connected with said expansion chamber adapted to pass air through said pulverizer, into said expansion chamber and from said chamber to a place of combustion, said chamber being adapted to retard the air stream passing therethrough and to cause coarser particles of pulverized material to fall back into said pulverizer, and regulatable means for admitting air near the top of said chamber for varying the mixture of air and pulverized material and for aiding the separation of the coarse and fine particles in the air stream.

4. A fuel apparatus of the character described comprising a reducing chamber provided with an annular pulverizing wall having a material inlet opening in the upper part thereof, a portion of said wall adjacent said inlet opening having a plurality of openings for the passage of air and fuel from the pulverizing chamber, a separating chamber located immediately above the pulverizing chamber and communicating therewith through the last mentioned openings, a fuel reducing chamber cooperating with said pulverizing wall and having means for discharging a current of air from the reducing chamber through the openings in said annular wall into said separating chamber, means for directing incoming material to the bottom of said reducing chamber and tangentially of the reducing member, a passage for conducting the ground material from the top of said separating chamber, and means in said passage for inducing a current of air through said passage.

5. A fuel apparatus of the character described comprising a grinding chamber having an air inlet and a separate material outlet, a separating chamber directly above the grinding chamber so as to receive material through said outlet, an elongated passage for conducting ground material from the top of said separating chamber to a place of use, a rotatable driving element extending through said grinding chamber and into said passage, a grinding member mounted on said driving element and located within said grinding chamber directly beneath said separating chamber so that said grinding members will throw the ground material directly through said material outlet into said separating chamber, and a suction device located within said passage and operatively connected with said driving element so as to induce a current of air to flow through the air inlet and into the grinding chamber

to separate the heavier particles from the finer particles of said material.

6. A fuel apparatus of the character described comprising a reducing chamber provided with an annular pulverizing wall having a material inlet opening in the upper part thereof, a separating chamber located immediately above the pulverizing chamber and communicating therewith, a fuel reducing member cooperating with said pulverizing wall to reduce the material and having means for discharging a current of air from the reducing chamber into the separating chamber, means for directing the incoming material to the bottom of said reducing chamber and tangentially of said reducing member, means for inducing an air current through said separator chamber so as to withdraw the pulverized material therefrom, and means in the separating chamber for returning the heavier particles of reduced fuel to the reducing chamber.

7. A fuel apparatus of the character described comprising a reducing chamber provided with an annular pulverizing wall having a material inlet opening in the upper part thereof, a portion of said wall adjacent said inlet opening having a plurality of openings for the passage of air and fuel from the pulverizing chamber, a separating chamber located immediately above the pulverizing chamber and communicating therewith through the last mentioned openings, a fuel reducing member cooperating with said pulverizing wall and having means for discharging a current of air from the reducing chamber through the openings in said annular wall into said separating chamber, and means for inducing an air current from the upper portion of said separator so as to withdraw the pulverized fuel from said separating chamber.

8. A fuel apparatus of the character described comprising a reducing chamber provided with an annular pulverizing wall having a material inlet opening in the upper part thereof, a separating chamber located immediately above the pulverizing chamber and communicating therewith through said inlet opening and also independently of said opening, a rotatable shaft extending through said reducing chamber parallel with said inlet opening, a fuel reducing member on said shaft disposed laterally with respect to said material inlet, said reducing member having elements cooperating with said wall to reduce the material, said members being constructed to discharge a current of air from the reducing chamber into the separating chamber, means for directing incoming material to the bottom of said chamber and tangentially of said reducing member, and means for inducing an air current from the separator through said conduit so as to

withdraw the pulverized fuel from said separating chamber.

9. A fuel apparatus of the character described comprising a reducing chamber provided with an annular pulverizing wall having a material inlet opening in the upper part thereof, a separating chamber located immediately above the pulverizing chamber and communicating therewith a fuel reducing member located within the reducing chamber and disposed laterally and parallel with respect to said material inlet, said reducing member having elements cooperating with said wall to reduce the material, said members being also constructed to discharge a current of air from the reducing chamber directly into the separating chamber, means for directing incoming material to the bottom of said reducing chamber and tangentially of said reducing member, and induction means connected with the top of said separating chamber to withdraw the pulverized fuel therefrom.

In witness whereof, I hereunto subscribe my name to this specification.
